David K. Homan, San Francisco, Calif., assignor to Homan & Co., Inc., Cincinnati, Ohio, a corporation of Ohio

Filed Mar. 2, 1960, Ser. No. 59,588

Term of patent 14 years

(Cl. D14—6)

The dominant features of my design reside in the portions shown in full lines.

I claim:

The ornamental design for a freight trailer standard, as shown and described.
